John Rogers of New York, N.Y.

DES. 2024

Letters Patent 1,292,234 Dated Jan. 17, 1914.

Design for a group of Statuary.

The schedule referred to in these letters patent and making a part of the same.

As all as hereinafter may concern:

Be it known that John Rogers, of the City and County of New York and State of New York, have invented or produced a new and original design for a group in Statuary, and do hereby declare that the following is a full and exact description of the same. The group is called "One more shot" and consists of two figures. One of them is standing. His left arm is wounded and he is taking out with his right hand a cartridge for another shot. The other one is sitting on his knapsack binding up his wound.

Having thus described my invention, what I claim and desire to secure by Letters Patent is: The design for a group of Statuary herein set forth and described, and as is fully shown in the accompanying drawings.
